United States Patent Office

Des. 197,872
Patented Mar. 31, 1964

197,872

VENTILATOR

Daniel S. Ekern, 1253 S. Truro Ave., Hawthorne, Calif.

Filed Jan. 22, 1963, Ser. No. 73,272

Term of patent 14 years

(Cl. D81—25)

Fig. 1

Fig. 2

Fig. 3

Fig. 4

FIGURE 1 is a front perspective view of a ventilator showing my new design; and

FIGURE 2 is a rear perspective view thereof.

FIGURE 3 is a front elevational view thereof;

FIGURE 4 is a side elevational view thereof.

The broken line showing of a stove and a fragmentary vent pipe in FIGURE 1 is for illustrative purposes only.

I claim:

The ornamental design for a ventilator, as shown and described.
